Mathew Dodge
Setters Patent

2/20/1835

The scheme arranged in these Setters Patent and making part of the same containing a description in the name of the said Mathew Dodge how to fit up his improvement in Water vehicles for Steam Boats which he de-
signates the Continuous straight buoyant wheel -

The continuous straight buoyant wheel
is constructed like a common Steam boat wheel except the shaft where
the blades are attached incline forward at an angle of 45 degrees. A brace
running from the outer edge of one blade or shaft to the angle of the other
shaft under the bow ^{will} make it strong.

This wheel though simple in its construction
when attached to a steam boat moves very well naturally buoying
up the boat and as the blade recedes from the water it is made not
to meet resistance which the common Steam boat wheel ^{inevitably} ~~is obliged~~
meets with; consequently a steam boat with wheels constructed
upon the model must pass through the water with much greater
velocity than with the commonly constructed wheel.

The speed of the boat can also be increased
by a wheel constructed after this manner much more than by the common
wheel as the natural tendency of a backward motion of the
wheel is to draw the boat down in the water.
